UNITED STATES PATENT OFFICE.

MARCUS E. COOK, OF WALLINGFORD, CONNECTICUT.

ROAD-SCRAPER.

SPECIFICATION forming part of Letters Patent No. 296,138, dated April 1, 1884.

Application filed November 10, 1883. (No model.)

To all whom it may concern:

Be it known that I, MARCUS E. COOK, of Wallingford, in the county of New Haven and State of Connecticut, have invented a new Improvement in Road-Scrapers; and I do hereby declare the following, when taken in connection with the accompanying three sheets of drawings and the letters of reference marked thereon, to be a full, clear, and exact description of the same, and which said drawings constitute part of this specification, and represent, in—

Figure 1, a top or plan view of the apparatus; Fig. 2, a side view; Fig. 3, a transverse section in front of the scraper; Fig. 4, a transverse section through the rocker.

This invention relates to an improvement in apparatus for leveling road-surfaces—that is to say, a scraper which is arranged upon a frame set on wheels, so that as the apparatus is drawn over the surface of the earth the scraper levels or evens the surface over which it is drawn. These scrapers require to be made adjustable to different angles to the path in which they are drawn, as well as horizontally.

The object of my invention is to form a firm support against the scraper and make that support adjustable to change the angle of the scraper to the path in which it is drawn; and in such construction, as more fully hereinafter described, and particularly recited in the claims, my invention consists.

A A are the two sides of the frame, supported on a rear axle, B, carrying wheels C C, the two sides extended forward and attached to a longitudinal rocker, D. This rocker is supported on a fifth-wheel, E, resting on the forward axle, F, which carries the forward wheels, G G, and to which the drawing power to move the apparatus is applied. About midway of the length of the frame—that is, between the front and rear wheels—a vertical abutment, H, is hung upon a pivot, a, and so as to be turned upon said pivot in a horizontal plane, but held in its bearings so as to prevent vertical movement or change of elevation with relation to the frame. At the lower edge of this abutment H a toothed segment, I, is fixed, concentric with the axis a, upon which the abutment will turn.

L is a vertical shaft, arranged in suitable bearings in the frame, and carrying at its lower end a pinion, M, corresponding to the teeth of the segment I, and so as to work therein. On the upper end of the shaft is a hand-wheel, N, by which the pinion may be turned to correspondingly turn the segment and abutment H. In front of the abutment is a scraper, P. Near each end this scraper is attached to a vertical sliding rod, R. These rods work freely up and down through bearings in the abutment-frame. The scraper is attached to the rods by a pivot, as at d. (See Fig. 2.)

To the abutment-frame levers S T are hung upon their respective fulcrums e f, their inner ends free, their outer ends connected by a rod, h, to the scraper, so that by depressing either lever—say S, Fig. 3—that end of the scraper will be raised, as seen in broken lines; or if the other lever be depressed, that end of the scraper will be raised accordingly; or if both be depressed, then the scraper will be raised bodily. By turning the hand-wheel N, the segment I, with the abutment H, is correspondingly turned, and because the scraper is in connection with or bears against the forward surface of the abutment it will be correspondingly turned, so that the scraper may be turned, say, from one angle (indicated in broken lines, Fig. 1) to the opposite angle, (indicated by broken lines, same figure,) and in so turning the scraper the levers in connection with it are correspondingly turned, so that they are always in the same relative position to the scraper for operation. The operator can stand upon the platform in rear of the abutment and over the segment, and there can operate the hand-wheel and the levers, as occasion may require. The abutment is sustained by a segment, i, (see Fig. 1,) which corresponds to its circular edge, the segment supported by braces l from the rear axle, the lower bearing for the shaft L being made as a part of the segment i. Thus the thrust is taken directly to the rear axle, and because of the adjustable abutment for the scraper it is always firmly held, and none of the mechanism in connection with the scraper and necessary for its adjustment changes its relation to the scraper in such adjustment, the whole mechanism of the scraper being moved with it in changing its angle to

the direction of the draft. The forward wheels pass over the ground which is to be leveled, while the rear wheels pass over the ground which has been leveled; hence the forward 5 wheels are liable to a constant change of position with relation to the frame—that is, one wheel may be up and the other down, and then vice versa within a short distance. In order that such rocking or change of position 10 to the forward axle may not interfere with the level of the frame which carries the scraper, I make the rocker D to stand in a position longitudinally central to the carriage, as seen in Fig. 1. The underside of this rocker is rounded, 15 and is of a length to bear upon the front and rear sides of the fifth-wheel E, and through this rocker the king-bolt m is arranged. Therefore the rocker only has a bearing in a longitudinal central line. This will permit the forward 20 axle to turn out of level in either direction, according to the unevenness of the ground, as seen in broken lines, without material effect upon the position of the frame which carries the scraping mechanism, which cannot be the case when a two-plate fifth-wheel is employed, 25 or a transverse bearing of any considerable length be made upon the forward axle.

By this construction of scraper the angle as to direction of movement or elevation is easily 30 adjusted and held in such position, and that position is not liable to be changed by the irregularities of the surface of the ground over which the forward wheels are obliged to travel.

I claim—

35 1. In a road-scraper, the frame supported upon an axle carrying wheels at the rear, and an axle carrying wheels at the front, a transverse abutment arranged upon said frame on a vertical axis, and made adjustable on said 40 axis to change the angle of the abutment with relation to the direction in which the apparatus is drawn, a scraper in front of and so as to bear against said abutment and partake of its adjustment in a horizontal plane, said scraper 45 adjustable vertically independent of said abutment, substantially as described.

2. In a road-scraper, the combination of the frame supported upon wheels at the front and

rear, an abutment hung to the frame between the front and rear wheels upon a vertical axis, 50 a toothed segment in connection with said abutment, a shaft and pinion working into said segment, whereby said segment and abutment may be turned to varying angles, a scraper arranged in front of said abutment and made 55 adjustable thereon, substantially as described.

3. In a road-scraper, the combination of the frame supported upon wheels at the rear and front, an abutment arranged upon a vertical axis in said frame between the front and rear 60 wheels, a toothed segment in connection with said abutment, a shaft and pinion working into the teeth of the segment, a scraper arranged in front of and so as to bear against said abutment, with a lever hung upon said abutment 65 at each side, each lever in connection with its respective end of the scraper, substantially as described.

4. In a road-scraper, the combination of a frame supported upon an axle carrying wheels 70 at the rear, and an axle carrying wheels at the front, a transverse abutment hung upon a vertical axis in said frame and made adjustable on said axis to different angles to the direction in which the apparatus is drawn, but held 75 in its bearings to prevent change of elevation with relation to the frame, a fixed segment, i, in rear of said abutment, the axis on which the abutment turns being the center of said segment, said segment supported by braces l l, 80 substantially as described.

5. In a road-scraper, the combination of a frame arranged upon wheels at the rear and front, and carrying an adjustable scraper between said front and rear wheels, the frame 85 at the front provided with a longitudinal rocker, D, resting in a longitudinal central line upon the fifth-wheel of the forward axle, and the king-bolt through said rocker, fifth-wheel, and axle, said rocker rounded upon its 90 under surface, substantially as and for the purpose described.

MARCUS E. COOK.
